UNITED STATES PATENT OFFICE.

GEORGE ELLIS, OF TRENTON, NEW JERSEY, ASSIGNOR TO MADDOCK POTTERY COMPANY, OF TRENTON, NEW JERSEY.

DESIGN FOR A PLATE OR SIMILAR ARTICLE.

Application filed May 16, 1923. Serial No. 6,171. Term of patent 14 years.

To all whom it may concern:

Be it known that I, GEORGE ELLIS, a citizen of the United States, residing at Trenton, in the county of Mercer and State of New Jersey, have invented a new, original, and ornamental Design for Plates or Similar Articles, of which the following is a specification, reference being had to the accompanying drawing, forming part thereof.

The figure is a plan view of a plate, showing my new design.

I claim:

The ornamental design for a plate or similar article, as shown.

GEORGE ELLIS.
